UNITED STATES PATENT OFFICE.

ROBERT FRICKE, OF WAIPAHU, TERRITORY OF HAWAII, ASSIGNOR OF ONE-FOURTH
TO ERNEST W. GREENE, OF WAIPAHU, OAHU, AND ONE-FOURTH TO WILLIAM G.
HALL, OF HONOLULU, TERRITORY OF HAWAII.

CANE CAR.

Application filed October 5, 1925. Serial No. 60,628.

The invention relates to improvements in cars for transporting sugar cane and the like and has for its object to provide a car of the platform type having end walls with longitudinal flexible connections between the upper corners of the end walls, each connection being provided with a releasable coupling intermediate its length, and pendant flexible connections between the longitudinal connections and the platform, said pendant connections being spaced at intervals and preferably detachably connected to the platform, said longitudinal and pendant connections constituting the load retaining means at the sides of the platform car, which facilitate the unloading of the car by releasing the couplings in the longitudinal connections and permitting both the longitudinal and pendant connections to collapse toward the end of the car, thereby leaving the entire side of the car open, so that the load may be readily discharged.

The invention is illustrated in the accompanying drawing, in which:—

25 The figure is a side elevation of the car.

Referring to the drawing, 1 indicates the platform of a car of the general type employed in transporting cane and like commodities, which are customarily loaded in the harvest fields and conveyed to the mill or other point of deposit. The car is provided with end walls 2, which may be of the usual type comprising corner posts and cross planking between the posts, the sides of the cars between the end walls being open and unobstructed.

In cars of this general type, it has been customary to provide the sides with stakes supported at intervals in stake pockets, or with hinged side walls adapted to be swung out to release the load. These types of cars have been found objectionable, when employed with the usual machine loaders, because of the size and weight of the bundles of cane or the like, which are deposited by the machines on the cars. The present invention avoids the objections and difficulties incident to the so-called stake cars and box cars and provides a simple, light, strong and durable retaining means, disposed on each side of the car between the end walls, as follows:

Flexible connectors, preferably in the form of chains 3 having detachable cou-

plings 5 intermediate their lengths, are secured to the upper corners of the end walls 2 of the car, preferably by eye bolts 4 passing through the corner posts of the end walls. One of these longitudinal connectors 3 is disposed on each side of the car in the manner shown, and connected to the longitudinal flexible members 3, at spaced intervals, are pendant flexible members 6, which are adapted to be connected at their lower ends to the platform 1, so that, when the longitudinal and pendant flexible connections are normally disposed as illustrated in the drawing, they constitute an exceedingly strong flexible side wall to retain the load of cane or the like on the car. Preferably the longitudinal and pendant flexible members are made up of chains and the couplings intermediate the lengths of the longitudinal chains may be any of the approved releasable catches.

It is preferred that the lower ends of the pendant chains or connectors 6 be detachably connected to the platform and, to this end, they may be conveniently provided with eyes 7 adapted to be slipped over the projecting ends of metal cross bars 8 secured to the platform 1 and having openings in the ends thereof to receive locking pins 9, which are secured to the platform by chains 10. If desired, the means for securing the lower ends of the pendant chains 6 may be in the form of a releasable rod running lengthwise of the side of the platform, said rod being passed through the lower links or eyes on the ends of the pendant chains and supported in suitable brackets on the side of the platform.

As indicated, after the car has been loaded with heavy bundles of cane, or the like, and conveyed to the unloading point, the coupling 5 in one or both of the longitudinal chains 3 is cast loose, thereby permitting the two sections of the longitudinal chain and the attached pendant chain 6 to fall toward the end of the car, leaving the entire side of the car open and unobstructed, so that the load of cane may be shifted immediately from the platform to a suitable carrier.

Among the particular advantages incident to this construction are that the cars are less expensive than those of the stake pocket and side door type, the cars are much lighter than those commonly employed for the same

purpose, the wear and tear on the chain construction will be much less than on the other types of cars, when mechanical cane loaders are used, and, as the chains are all permanently attached to the car, neither the chain sections nor their associated elements can be lost or fall accidentally into the carrier and go into the mill, which is a difficulty commonly experienced with stake cars and the like.

What I claim is:

1. A car for transporting sugar cane and the like having end walls and open sides above the platform, longitudinal flexible members extending between and connected to the upper corners of the end walls and having releasable couplings intermediate their lengths, and pendant flexible members extending between and connected to the longitudinal members and the platform.

2. A car for transporting sugar cane and the like having end walls and open sides above the platform, longitudinal flexible members extending between and connected to the upper corners of the end walls and having releasable couplings intermediate their lengths, and pendant flexible members extending between and connected to the longitudinal members and the platform and releasably connected to the latter.

3. A car for transporting sugar cane and the like having end walls and open sides above the platform, longitudinal chains ex-

tending between and connected to the upper corners of the end walls and having releasable couplings intermediate their lengths, and pendant chains connected to the longitudinal chains extending to and connected with the platform.

4. A car for transporting sugar cane and the like having end walls and open sides above the platform, longitudinal chains extending between and connected to the upper corners of the end walls and having releasable couplings intermediate their lengths, and pendant chains connected to the longitudinal chains extending to and releasably connected with the platform.

5. A platform car having end walls, longitudinal chains extending between the upper corners of the end walls and having releasable couplings intermediate their lengths, pendant chains connected to said longitudinal chains at spaced intervals, and means for securing the ends of the pendant chains with the platform.

6. A platform car having end walls, longitudinal chains extending between the upper corners of the end walls and having releasable couplings intermediate their lengths, pendant chains connected to said longitudinal chains at spaced intervals, and means for releasably securing the ends of the pendant chains to the platform.

In testimony whereof I affix my signature.

ROBERT FRICKE.
